JEWELRY BOX

Paul Selwyn, 1565 Clubview Drive,
Los Angeles, Calif. 90024

Filed May 1, 1968, Ser. No. 11,736

Term of patent 14 years

Int. Cl. D3—99

U.S. Cl. D87—1

The broken line showing of a ring in FIGURE 1 is for illustrative purposes only.

I claim:

The ornamental design for a jewelry box, as shown and described.
